United States Patent Office

Des. 178,900
Patented Oct. 2, 1956

178,900

STADIUM SEAT

Ralph A. O'Neill, Huntington, W. Va.

Application September 23, 1953, Serial No. 26,916

Term of patent 14 years

(Cl. D15—8)

Fig. 3.

Fig. 4.

Figure 1 is a perspective view of a stadium seat in open position showing my new design; and

Figure 2 is a view thereof in side elevation in open position.

Figure 3 is a front view thereof shown in folded position;

Figure 4 is a side view thereof shown in folded position.

A characteristic feature of the design resides in the relationship of the webbed back rest element and the webbed seat element, wherein the webbing of these two elements when in folded position forms a substantially continuous webbed area.

I claim:

The ornamental design for a stadium seat, as shown and described.
